UNITED STATES PATENT OFFICE.

WILLIAM SPARKS, THEODORE JOHNSON SCOFIELD, FRED W. BILLIG, AND LLOYD E. JOHNSON, OF JACKSON, MICHIGAN, ASSIGNORS TO THE SPARKS-WITHINGTON COMPANY, OF JACKSON, MICHIGAN, A CORPORATION OF OHIO.

SIGNALING DEVICE.

Application filed December 21, 1926. Serial No. 156,132.

This invention relates to certain new and useful improvements in signaling devices.

The main object of the invention is the production of a novel signaling device particularly designed for use on automobiles, motor boats and the like, and capable of producing a comparatively loud signal that will carry long distances, and is of a musical tone or a combination of musical tones preferably of a harmonious character.

More detailed objects relate to the simplicity and strength of the structure and the detailed form, arrangement and association of the parts thereof, all as will more fully appear from the following description taken in connection with the accompanying drawings, in which:

Figure 1 is an elevation of a signaling device of this invention.

Figure 2 is a section on line 2—2, Figure 1. Figure 3 is a vertical section through the device taken at right angles to Figure 2.

The structure as herein illustrated consists of a rotary electric motor —1— having a front wall —2— of substantially circular form, formed with a tubular boss —3— in which the forward end of the armature shaft —4— is journaled.

The rear end of the armature shaft —4— may be mounted in an adjustable bearing —5— carried by the end or cross-wall —6— of a U-shaped motor case —7—, the ends of which are connected to the flanges —8— and —9— respectively formed upon the front wall —2—. The usual armature —10—, pole pieces —11— and field coils —12— are provided.

The actual structure of the motor may vary widely as it constitutes a preferred driving means for the rotor —13— of a rotary compressor, and for this purpose the end wall or head —2— is formed with a circular chamber or cylinder —14— eccentric with respect to the armature shaft —4— and to the rotor shaft —15— which is aligned with the armature shaft —4— and may, as shown, have a threaded relation with the rotor —13— and its rear end is formed with a tongue adapted to lie within the boss —3— for interlocking engagement with the forward end of the armature shaft —4— which is formed with a groove for receiving the tongue —16—, thereby permitting some relative movement of the armature and rotor

shafts without interfering with the driving connection. The armature and rotor shafts are in effect a sectional armature shaft and may be so considered.

The end head —2— is further formed with an air-storage chamber —17—, in this instance concentric with the cylindrical chamber —14— and extending around the cylindrical chamber throughout more than half its circumference, and in communication with the cylindrical chamber through port —18— in the wall of said chamber, and through which port air under pressure is ejected by the rotor —13— from the chamber —14—. For effecting this result, the rotor includes one or more, in this instance three movable blades —19— slidably mounted in grooves or recesses in the rotor, and preferably spaced equal distances apart and adapted to be thrown out by centrifugal force as the rotor —13— is driven by the armature shaft —4—.

The compressor chamber —14— is formed with an air inlet provided by the tube —20— which penetrates the wall of the chamber —13—, extends across the chamber —17— and penetrates the external wall of the chamber —17—. The inlet —20— is at the low pressure side of the rotary compressor and the outlet —18— at the high pressure side.

When the rotor is set in motion by rotation of the armature shaft —4—, the air compressed in the chamber —14— escapes through outlet —18— into the storage chamber —17— and thence into the air-conveying tube —21—.

A plurality of air resonant devices —22— are connected to the air-conveying tube —21—. In this particular illustration two such horn or air resonant structures are shown and adapted to produce musical tones or notes of varying pitch. These air resonant structures each comprise a casing —23— formed of two parts —24— and —25— threaded together at their edges to form an enclosed chamber. The portion —24— is substantially cup-shaped and internally threaded and formed at the central portion of its bottom wall with a tubular boss or nipple —85— externally threaded and adapted to be screwed into an internally threaded opening in the forward wall of the air-conveying tube —21—.

The other portion —26— is formed with a

circumferential flange —27— externally threaded and screwed into the open end of the cup-shaped member —24—. The forward member —26— is connected to the projector —28— in any suitable manner, and is formed with a circular flange —30— axially aligned with both the projector —28— and the nipple —25— and projecting rearwardly into the chamber within the casing —23—.

10 The rear face of the flange —27— is preferably formed with an outwardly and forwardly inclined portion constituting a groove —31— and on the inclined bottom wall of which the outer edge of a thin disk 15 —36— of suitable material, such as metal, is adapted to be confined by the forwardly and outwardly inclined front face —32— on the outer edge of a plate —34—.

In this particular illustration, the upper 20 casing —23— is somewhat larger than the lower casing and the plate —34— in both instances is formed with a plurality of openings which, as shown, are concentrically arranged near the outer edge of the plate to 25 permit the passage of air through the plate to the thin disk —36— which is also formed with openings or perforations.

The disk —36— arranged in the upper and larger casing —23— is formed with 30 three openings concentrically arranged near the outer edge of the disk and outside the circular flange —30—, whereas the disk —36— in the lower casing has its edge formed with grooves or recesses which permits the passage of air from tube —21— to the portion of the chamber within casing —23— forward of the disk —36—.

The two projectors —28— should be made to suit the respective air supplying mechanisms to produce the desired tone, and are as shown, of different length, the longer one being connected with the smaller casing —23—. These projectors extend substantially parallel with the axis of the motor 45 and overlie the motor, thereby producing a compact device. A bracket —90— may be attached to the compressor casing for supporting the horn, or any other suitable means may be utilized.

50 The edge of flexible disk —36— is confined upon an outwardly and forwardly inclined surface, and the disk —36— and plate —34— are both clamped between the two sections of casing —23—, with the 55 result that the central portion of the disk —36— tends to bow rearwardly away from the opening in the flange —30— leading to the projector —28—.

The sound-producing faculty of the 60 resonant devices results from the alternate opening and closing of the conduit within the flange —30— which extends rearwardly from the projector —28— by movement of the disk —36—.

65 It will be apparent that the structure is

of compact and stable form and construction, and the resulting signal is of a musical character, or of a harmonious character as a result of the combination of two or more musical tones of preferably different pitch. 70

The resulting signal is pleasing, and has unusual carrying power, and is highly efficient for use in connection with moving vehicles, and altho I have shown and described a specific structure as illustrative of 75 a perhaps preferred embodiment of the invention, I do not desire to restrict myself to the details of the structure or the parts thereof, as various changes and modifications may be made within the scope of the 80 appended claims.

I claim:

1. A horn comprising a fluid compressor including a rotor chamber and a rotor arranged therein, a storage chamber partially encircling the rotor chamber and in communication solely with the high pressure side of the compressor, an air resonant device in communication with the storage chamber, and a tube penetrating the exterior wall 90 of the storage chamber and the wall of the rotor chamber on the low pressure side of the compressor.

2. A horn comprising a rotary motor, a compressor and a plurality of air resonant devices extending substantially parallel with the axis of the motor. 95

3. A horn comprising a rotary motor, a compressor and a plurality of air resonant devices extending substantially parallel 100 with the axis of the motor and rearwardly of the motor in a direction away from the compressor.

4. A horn comprising a rotary motor, a compressor and an air resonant device 105 extending substantially parallel with the axis of the motor and overlying the motor.

5. A signaling device comprising a motor, a fluid compressor including a compressor chamber and a rotor therein driven by the motor, a storage chamber in communication with the compressor chamber, a diaphragm chamber, means of communication between the storage chamber and the diaphragm chamber, a tube extending into the diaphragm chamber, and a vibratory disk 110 extending across the open end of the tube and having openings therethrough out of registration with the tube. 115

6. A horn comprising a rotary motor, a compressor and an air resonant device comprising a diaphragm chamber, a plate in the diaphragm chamber, a plurality of apertures in the plate, a diaphragm adjacent 125 one face of the plate, said diaphragm having a plurality of cut-away portions in spaced relation about its edge, and a tube coaxial with the diaphragm and positioned to be contacted thereby when the diaphragm is 130 vibrated.

7. A horn comprising a rotary motor, a compressor and an air resonant device comprising a diaphragm chamber, a plate in the diaphragm chamber, a plurality of apertures in the plate, a diaphragm adjacent one face of the plate, said diaphragm having a plurality of apertures in spaced relation about its edge and a tube having one end adjacent the diaphragm and adapted to be contacted thereby when the diaphragm is vibrated. 10

In witness whereof we have hereunto set our hands this 30th day of November 1926.
